UNITED STATES PATENT OFFICE.

ANDREW J. LEEDOM, OF TURLOCK, CALIFORNIA.

DRAG.

Application filed March 28, 1927. Serial No. 179,041.

My present invention has reference to a road surfacing machine or drag, and my object is the provision of a machine for this purpose in which the blades are so arranged as to cause the road surface to travel at different angles therebetween so that all of the dirt will be equally distributed over the road.

A further object is the provision of a road surfacing machine or drag having angularly arranged blades which are mounted, in a novel manner on a wheeled frame, and in which means, operable from the front of the machine, is employed for vertically adjusting the rear or ground wheels one with respect to the other to cause the frame and the blades to assume desired angles, there being also means for vertically adjusting the front or guide wheels of the machine that is likewise operable from the front of the machine.

A still further and important object of the invention is the provision of a road surfacing machine and drag, which includes a frame mounted on wheels, the said frame carrying angularly arranged road contacting blades, while pivotally associated with the frame there is an auxiliary frame also carrying blades, there being means for adjusting and sustaining the auxiliary frame angularly with respect to the main frame, while on the rear of both of the frames there is a blade made up of two hingedly connected sections, one of said sections being swingable with the auxiliary frame, and the other section being attached to the main frame, said rear blade being pivotally supported whereby the same may be swung at any desired angles with respect to the machine and also whereby the natural crown of the road is maintained and the rear or spreader blade may be swung and sustained at such angles as to direct the dirt either to the center of the road or to the gutter at the side thereof.

A still further object is the provision of a road surfacing machine or drag which includes blades arranged in cooperating series, one series of blades being disposed at an opposite angle to that of the other series, means being provided for raising the blades out of road contacting engagement or for lowering said blades to desired degrees of road contact, the improvement also including a rear or spreader blade which is made up of a fixed section in a line with one of the series of the first mentioned blade and

a hinged section in a line with the second series of blades, there being means for swinging the hinge section simultaneously with the said series of blades and there being further means for swinging the rear sectional blade horizontally and sustaining the same to any desired angle with respect to the first mentioned blades.

To the attainment of the foregoing broadly stated objects and many others which will appear as the nature of the invention is better understood, the improvement further resides in certain other novel features of construction, combination and operative association of parts, a satisfactory embodiment of which is disclosed by the accompanying drawings.

In the drawings:

Figure 1 is a plan view of my improvement.

Figure 2 is a sectional view approximately on the line 2—2 of Figure 1.

Figure 3 is a fragmentary side elevation of the improvement.

Figure 4 is a sectional view approximately on the line 4—4 of Figure 1.

Figure 5 is a detail horizontal sectional view approximately on the line 5—5 of Figure 3.

Figure 6 is a detail view, with parts in section, to illustrate the manner in which the auxiliary frame is hingedly secured to the main frame.

Figure 7 is a sectional view approximately on the lines 7—7 of Figure 1.

Figure 8 is a sectional view approximately on the line 8—8 of Figure 1.

Figure 9 is a sectional view approximately on the line 9—9 of Figure 4.

Figure 10 is a sectional view approximately on the line 10—10 of Figure 2.

As disclosed by the drawings I make use of a substantially rectangular frame 1. The frame is preferably formed of I beams that have their ends firmly riveted together and the side members of the frame connected by suitable brace beams. The end members of the frame are connected by a longitudinal beam 2 that is secured to the said ends at a point beyond the center of the frame 1, and the cross beams are also connected to the said beam 2.

Journaled in suitable bearings 3—3 and 4—4 arranged respectively on the beam 2 and the side beams of the frame 1 there are shafts 5 and 6, respectively. These shafts

have their ends, outward of the bearings 4, cranked and the outwardly projecting portions of the said cranked ends form spindles for ground wheels 7. The ground wheels 7 are arranged adjacent to the rear of the frame 1, and each of the shafts 5 and 6 has fixedly secured thereto an upwardly extending arm 8. To the outer end of each arm 8 there is pivoted a bar 9 that has a rack surface 10. The bars 9 are guided through substantially U-shaped uprights 11 that are secured to one of the cross beams 12 for the frame. The lower edges of the bars 9 rest on rollers 13 that are suitably journaled between the arms of the U-shaped uprights 11. Each upright 11 is connected by the angle ends of a plate 14 to an upright 15 that is also supported on the transverse brace beam 12. Journaled through suitable bearing openings in the U-shaped uprights 11 and in the straight uprights 15 there are shafts 16. On the portions of the shafts received between the U-shaped uprights 11 there are fixed toothed wheels 17 that are in mesh with the rack surfaces 10 on the bars 11, and on the ends of the shafts 16 which extend through the uprights 15 there are fixed worm wheels 18. The worm wheels 18 are in mesh with worms 19 on shafts 20 that are supported in suitable bearings and are directed toward the front of the device. The outer ends of these shafts have secured thereon hand wheels 21. By operating either of the hand wheels it will be apparent that a swinging movement will be imparted to one of the wheel supporting crank shafts, so that one of the ground wheels 7 may be vertically adjusted with respect to the second ground wheel. Also incident to the toothed engagement between the worms 19 and the worm wheels 18 the crank shafts 5 or 6 will be effectively sustained in adjusted position.

Secured to the front of the frame there is a yoke 22 through which the forward ends of the shafts 20 pass, and the hand wheels 21, as disclosed by Figure 1 of the drawings, may have secured thereon crank handles 23.

Fixedly secured to the sides of the frame 1, at the front thereof, and clamped to the channel iron of the said front of the frame there are inwardly inclined bars in the nature of hounds 24, the said bars or hounds having their outer ends formed with straight extensions between which there is arranged, and to which there is bolted, the hollow headed end 25 of a rearwardly extending bar 26. The rear inner end of this bar 26 is fixedly secured to a laterally extending brace bar 27 that is fixed to one of the beams 2. The portion of the bar 26, adjacent to its headed end 25, is arched, the hound members 24 being arched at points

opposite the arched portion 28 of the bar 26 and this arrangement permits of the free turning of the guide wheels 29 at the front of the machine. The guide wheels are journaled upon spindles on the ends of an axle 30. This axle supports thereon a block or bearing 31 in which is swiveled a screw 32 that passes through aligning openings in the head 25. Threaded on the screw and finding a bearing between the opposite walls in the open head 25 there is a hub member that carries a gear 33. This beveled gear 33 is in mesh with a similar gear 34 that has a stub shaft journaled in a bearing in a bracket 36 which is preferably integrally formed on one side of the head 25. The shaft for the beveled gear 34, between the arms of the bracket 36 has fixed thereon a worm wheel 37, the said wheel being in mesh with a worm 38 on a shaft 39 that is suitably journaled in the bracket 36 and in the mentioned yoke 22. On the outer end of the shaft 39 there is a hand wheel 40, and this wheel may be also provided with a hand grip 41. It will be apparent that by turning the hand wheel the bolt or screw member 32 will be adjusted vertically through the head 25, so that the frame may be raised or lowered with respect to the ground wheels 29. The block or bearing 31 for the screw 32 has pivotally connected therewith a rod 42 that has an offset end, and the offset end of this rod is designed to be passed through one link of a chain 43 that has its end link secured to an eye or clevis 44 that projects from the lower edge of the head 25, and this chain 43 is designed to be attached to a tractor or like means for propelling the machine. On the mentioned transverse member 27, below the bar 26 there are secured rearwardly extending plates disposed at opposite angles so that the same are V-shaped in plan and these plates provide dirt deflectors 45. Fixedly secured to the beam 2, in a line with one of the angle deflectors 45 there is an angle plate 46, and on the outer face of this plate there is fixedly secured, a cross sectionally arched and curved scraper blade 47. Forward of the blade 47 and fixed to one side of the frame 1 and to the said beam 2, and arranged at an opposite angle with respect to the blade 47 there is a second and similar blade 48. The blade 47 is comparatively short, but the blade 48 extends beyond one of the sides of the frame. Also fixed between the mentioned side member of the frame 1 and the longitudinal brace member therefor, to the rear of the blade 47, and arranged at the same angle as the blade 48, there is a blade 49. It is, of course, to be understood that the blades 48 and 49 are curved in cross section and are secured to body or brace plates similar to the plate 46, for the blade 47.

The auxiliary frame is indicated broadly by the numeral 50, and is preferably constructed of I beams. Fixedly secured, adjacent to the ends in the outer channel of the inner side member of the auxiliary frame there are trunnions 51 whose ends are received in bearings 52 that are fixedly secured to the end members of the main frame 1. It is to be noted that the inner member 5 of the auxiliary frame is disposed a distance away from the center of the main frame approximately equalling the distance at which the beam 2 is spaced from the said frame, and that the outer beam of the auxiliary frame is disposed a suitable distance inwardly from the side beam of the main frame to which the blades 48 and 49 are fixed. The auxiliary frame has secured to the forward end thereof a cross sectionally 10 curved blade 53 arranged opposite the blade 48 and disposed at the same angle as the blade 47, and has also fixed thereto a blade 54 disposed opposite the blade 49 but arranged at the same angle as the blade 53. 15 These blades have their frames fixed to both the inner and outer side members of the auxiliary frame 50, while fixed to the inner side member of the auxiliary frame, disposed opposite the blade 47, but arranged in the same plane or angle as the blade 48 there is a blade 55. It will thus be noted that the central blade carried by the auxiliary frame is disposed at an opposite angle with respect to the other blades which are fixed thereto, which, of course, is true with respect to the blades that are fixed to the main frame and by such arrangement it will be noted that the dirt on the road, being contacted by all of the blades will be caused 20 to take a tortuous path when the machine travels over the road so that the dirt will be evenly distributed and a smooth road surface presented.

Journaled in suitable upright bearings 56 on the side member of the main frame, adjacent to the auxiliary frame 50, there is a longitudinally extending shaft 57. Having one of their ends secured to this shaft there are chains or like flexible elements 58. The elements 58 are wound around the shaft and have their second ends fixedly secured to the outer side member of the auxiliary frame 50. The shaft 57 has a universal joint connection 59 and a short shaft extension 60 and the shaft extension 60 in turn has a universal connection 61 with an operating shaft 62. The shaft 62 is journaled in suitable bearings on the forward end of the main frame and through a bearing opening in the outer element of the yoke 22. Fixed on the outer end of the shaft 62 there is a ratchet wheel 63 and journaled on the said shaft are the bifurcated arms of an operating lever 64, the arms of the said lever straddling the ratchet wheel 63, while pivoted be-

tween the said arms there is a dog 65 to engage with the ratchet wheel. By operating the lever 64 it will be apparent that the shaft 57 will be turned so that the auxiliary frame may be swung on its pivots 51 at desired angles with respect to the main frame or flush with such main frame. To hold the universally connected shafts from free turning there is fixed on the upper end of the shaft 62 a pawl wheel 66 and on the outer member of the yoke 22 a pivoted pawl 67 to engage with the teeth of the wheel 66.

The cross brace 27 is pivotally secured, as at 68, to the inner side of the auxiliary frame, and fixed on the inner side of the beam 2, to the rear of the scraper blades 49 and 50 there is a laterally extending member which may be termed a brace and which is indicated by the numeral 69. This member 69 is pivoted, as at 70, to the inner side member of the auxiliary frame 50. On the lateral extension or brace member 69 there is fixedly secured a block 71. As disclosed by Figure 9 of the drawings, this block may be in the nature of a channel member and has passed through the horizontal flanges thereof a headed bolt 72. The end of this bolt that passes through the top of the block is engaged by the threaded bore of one end of a crank handle 73. The bolt 72 passes through an opening in the upper flange of an angle plate 74. This angle plate is of a length to extend beyond the side of the main frame to which the blades 48 and 49 are secured, the said side member of the main frame having arranged thereover a plate 75 through which passes bolt members 76 that contact with the opposite edges of the said side member of the main frame, the said bolts also passing through an elongated opening 77 in the horizontal flange of the angle plate 74 and likewise through openings in a plate 78 arranged on the under face of the said flange. Fixed on the vertical flange of the angle plate 75 there is a scraper blade 79. By this arrangement it will be noted that the blades 79 may be swung horizontally to desired angles on the main frame and by tightening the screws 80 on the bolts 76 and by turning the crank handle 73 the said plate may be effectively sustained at such angles.

The inner end of the plate 74 terminates a slight distance from the inner side of the auxiliary frame 50, and this angle plate 74 has its outer edge concaved for the reception of the rounded end of a similar plate 81. The plate 81 is pivotally connected to the plate 74 by means 82, and on the vertical flange of the plate 81 there is secured a blade 83 similar to the blade 79. The horizontal flange of the plate 81 is secured to the outer longitudinal beam on the auxiliary frame 50 by means similar to those

which connect the plate 74 to the main frame, that is, through the medium of spaced bolts 84 that pass through elongated slots 85 in the horizontal flange of the plate 81, 5 the said bolts also passing through openings in a lower plate 86 that underlies the horizontal flange of the plate 81 and through an upper plate 87 arranged over the outer I beam member of the auxiliary frame, 10 these bolts having threaded thereon nuts 88. By this arrangement it will be noted that the blade 83 may be swung in unison and sustained at the same angle as the blade 79, but further it will be noted that the hinged 15 connection between these blades permits of the blade 83 assuming any desired angle with respect to the blade 79. Of course, it is to be understood that the downward swinging of the blade 83 is accomplished by 20 the operation of the shaft 57 and is in unison with the swinging of the remaining blades attached to the auxiliary frame. By arranging the blade 79 with the hinged extension 83, the last mentioned blades, together 25 with the blades on the auxiliary frame when the latter is permitted to move downwardly, scrape the road bed in a manner to maintain the natural crown of the road. The rear sectional blade, when swung horizontally, will engage with and direct the dirt to either the center of the road or to the gutter along the side of the road, and the simplicity of my construction and the advantages thereof will, it is believed, be fully 30 understood and appreciated by those skilled in the art to which such invention relates, when the foregoing description has been read in connection with the accompanying drawings.

40 The nature of my invention is such as to necessarily render the same susceptible to changes in size, proportion and in details of construction, and, therefore, it is to be understood that I have herein set forth 45 only one of a number of satisfactory embodiments of my invention and that I am not to be restricted thereto, but may make such changes and modifications therefrom as fairly fall within the scope of what I claim, 50 providing such changes do not sacrifice any of the advantages of my improvement.

Having described the invention, I claim:—

1. A road drag comprising a substantially rectangular main frame having a comparatively short angularly arranged scraper blade secured thereto, and longer scraper blades arranged at the same angle but at different angles with respect to the first mentioned blade, which latter extends beyond one side 55 of the frame, an auxiliary frame pivotally supported in the main frame having similarly arranged scraper blades thereon, a longitudinally extending shaft journaled on the main frame, flexible elements thereon 60 wound therearound and secured to the aux-

iliary frame, means for rotating the shaft, to arrange the auxiliary frame angularly with respect to the main frame and means for holding said shaft from rotation.

2. A road drag including a main frame 70 supported on ground wheels and on guide wheels, said frame having a comparatively short scraper blade thereon arranged at an angle with respect to the frame and having longer scraper blades to the opposite side 75 of the first mentioned blade arranged at an angle to said first mentioned blade, an auxiliary frame pivotally supported in the main frame and having blades fixed thereon disposed at the same angle and arranged 80 opposite the blades on the main frame, means for swinging the auxiliary frame to arrange the blades thereon angularly with respect to the blades of the main frame and means for adjusting the ground wheels and 85 the drive guide wheels vertically with respect to the main frame.

3. A road drag including a substantially rectangular main frame, having a comparatively short angularly arranged inner 90 ground scraping blade thereon and having longer ground scraper blades arranged to the opposite sides of the first mentioned blade, an auxiliary frame pivotally secured on the main frame, and having inner and 95 outer blades arranged at different inclinations from the blades on the main frame, an angular deflector carried by the frame between the inner blades of the main and auxiliary frames and means for swingably 100 adjusting the auxiliary frame with respect to the main frame.

4. A road drag comprising a substantially rectangular frame, supported on ground 105 wheels and on guide wheels, means for independently adjusting either of the ground wheels with respect to the frame, means for simultaneously adjusting the guide wheels with respect to the frame, a central and outer scraper blades secured on the frame, 110 an auxiliary frame pivotally secured to the main frame, scraper blades on the auxiliary frame arranged opposite but at different angles to the blades on the main frame, means for swingably adjusting the auxiliary 115 frame with respect to the main frame, a gathering blade to the rear of the first mentioned blades, including a section which is pivotally supported on the main frame and swingable horizontally thereon and a second 120 section which is hinged to the first mentioned section supported by and swingable on the auxiliary frame.

5. A road drag including a substantially rectangular main frame, and an auxiliary 125 frame arranged in and pivotally secured to the end of the main frame, ground wheels for the main frame, means for independently adjusting either of the ground wheels vertically with respect to the frame and for 130

sustaining the said wheels so adjusted, to the blades on the main frame, a blade means for vertically adjusting the steering wheels with respect to the frame, and both of said adjusting means being operable from the front of the frame, a longitudinal beam connecting the ends of the main frame and disposed to one side of the auxiliary frame, transverse brace means for the main frame, members extending laterally from the beam and pivotally secured to the auxiliary frame, a substantially V-shaped deflector carried by the forward brace, a comparatively short angle blade supported from the beam and arranged in a line with one of the angle sides of the deflector, other blades secured between the beam and one side of the main frame and arranged in the same plane and at different angles to the first mentioned blade, similar blades carried by the auxiliary frame, but arranged opposite and at different angles
